Primary Examiner — Susan Bennett Hattan*Assistant Examiner* — Lauren D McVey(74) *Attorney, Agent, or Firm* — Westerman, Hattori, Daniels & Adrian, LLP(57) **CLAIM**

The ornamental design for a stamp, as shown and described.

DESCRIPTION

FIG. 1 is a front perspective view of the stamp according to our novel design,

FIG. 2 is a rear perspective view thereof;

FIG. 3 is a front elevational view thereof;

FIG. 4 is a rear elevational view thereof;

FIG. 5 is a right side elevation view thereof;

FIG. 6 is a left side elevational view thereof;

FIG. 7 is a top plan view thereof; and,

FIG. 8 is a bottom plan view thereof.

The broken lines depict portions of the article that form no part of the claimed design.

1 Claim, 3 Drawing Sheets(56)
